UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

ROOFING MATERIAL

Application filed June 30, 1920, Serial No. 393,016. Renewed July 5, 1927.

This invention relates to sheet roofing materials or surfacing materials, and has special reference to the means provided upon or for use in connection with such materials, through which to adapt certain areas of the material for seaming or jointing with or adhering to the building structure or other portions of the material with which it may be associated in use.

10 Accordingly, the invention consists primarily in providing a mastic joining strip of sheet roofing or surfacing material, adapted for application to such roofing or surfacing material, and this strip consists of a suitable 15 vehicle, such, for instance, as felt, fabric, or other fibrous vehicle permeated by a mastic material which adapts the strip to serve as a cementing element, packing element, or the like.

20 In order that the invention may be fully understood, several embodiments thereof are disclosed by way of illustration in the accompanying drawings.

In said drawings—
25 Figures 1, 2, 3, 4, and 5 are perspective views of the joining strip and the method of associating it with the roofing sheet, whereby its adhesive surface may be protected from contact with extraneous surfaces until the 30 material is put into use.

Figures 6, 7 and 8 are further modifications of a method of applying a joining strip and protecting its adhesive surface from premature contact.

35 As suggested in Figures 1 to 5, inclusive, strips may be applied to the sheet 1 in various manners with the effect of protecting their adhesive surfaces until it is desired to use the sheet, when the strip may be turned up to expose its adhesive surface for contact with an adjoining sheet or article of roofing material that enters into the roofing structure.

In Figures 1 and 2, the turning up of the strip 2a exposes an adhesive area of both the 40 sheet and the strip; while in Figures 3, 4 and 5, the strip is folded upon itself so that it either exposes only its own surface when unfolded, or a portion of its own surface and an adhesive surface of the roofing sheet. In Figure 45 5, a folded strip 2b is provided with the

additional element of a gripping margin 2c through which to draw the strip away from the sheet when the sheet is to be put into use.

In Figures 6 and 7 the folded strip 2b is countersunk in the sheet 1, and the countersink is of such lateral dimension as will accommodate the strip when unfolded and present for adhesion to an adjoining piece of roofing material a mastic surface equal to the combined width of the strip when unfolded. 55

In Figure 8, a strip 2d of lap cement is covered with a strip 2e of fabric in a manner to be exposed by the folding back of the fabric, which also has the effect of presenting an adhesive face of the fabric to an overlapping 60 piece of roofing material. 65

There is an especial advantage with all of the forms shown in Figures 1 to 8, inclusive, in that the mastic material is pocketed or enveloped in a manner to not only avoid contact of the adhesive surfaces in the roll, but to prevent flowing of the mastic when the roll 70 is stood on end.

The various forms of joining strips herein described may be marketed in proper form 75 for application to the roofing sheet, as, for instance, by rolling the strip and shipping it in suitable wrappers, but it is preferably applied to the sheet in the factory.

The mastic with which the seaming or joining strip is impregnated may be of varying character according to the method of using it. The asphalt may be asphaltic, bituminous or any other desired material. It may have the inherent quality of lasting 80 stickiness or adhesiveness so that when exposed it renders the roofing material immediately self adhering; or it may be compounded more with a view to affording a packing substance between overlapped sheets 85 of material so as to render weather-proof a joint that is primarily held by nailing; or it may contain a non-drying oil which will be given off gradually into the impregnating substance of an overlying sheet with the effect 90 of dissolving such substance and developing a gradual cementing action at the joint; or it may be of such nature that it will be normally non-adhesive, but may be readily rendered adhesive by painting over its exposed 95 100

surface a suitable reagent that will sufficiently dissolve it to cause it to adhere to contacting surfaces. This latter method may likewise be applied to a roll of the seaming tape or strip just previous to putting it into use.

5 Mastics having the inherent quality of adhesiveness when in normal state and suitable for rendering roofing or other sheet surfacing material self-adhering without the use of heat or other media at the time of applying the surfacing material to its place of use, are readily obtainable from dealers in the open market when specified in terms of function to be performed. Such mastics are disclosed in my co-pending application Serial No. 336,713, filed November 8, 1919. It is to be understood that the present invention is not limited to any particular formula for the production of a mastic having the inherent 10 quality of remaining adhesive until after the covering material is applied at its place of use, and where it encounters exposure resulting from removal of the original package in which it is sold.

20 25 I claim:

1. The herein described sheet roofing or surfacing material having located upon seaming, jointing, or adhering areas thereof a mastic jointing strip having the inherent 30 quality of adhesiveness in its normal state; said strip having its jointing surface presented normally inward, and being movable relatively to the sheet to present its said surface outwardly for contact.

35 2. Sheet roofing or the like carrying upon seaming or jointing areas thereof a normally adhesive mastic substance, and a member normally enclosing said mastic but adapted to unfold to expose the same.

40 3. A roofing sheet or the like having thereon a normally adhesive mastic seaming member folded upon itself, and having upon its faces which are opposed in folding a mastic substance which is exposed for contact by the 45 unfolding of the strip.

4. A roofing sheet or the like having thereon a mastic seaming member folded upon itself, and having upon its faces which are opposed in folding a normally adhesive mastic 50 substance which is exposed for contact by the unfolding of the strip; said strip being countersunk in the sheet, and the countersink being of a width that accommodates the strip when unfolded.

55 Signed at Chicago, Illinois, this 25th day of June, 1920.

ALBERT C. FISCHER.
